METHOD OF PRODUCING ENERGETIC PLASMA FOR NEUTRON PRODUCTION

Persa R. Bell, Albert Simon, and Robert J. Mackin, Jr., Oak Ridge, Tenn., assignors to the United States of America as represented by the United States Atomic Energy Commission

Filed Aug. 7, 1958, Ser. No. 753,846

5 Claims. (Cl. 204—154.2)

This invention relates to a novel device for producing energetic neutrons and for heating a plasma and method of operation thereof.

Prior work in this field which laid the groundwork for the devices described herein consisted of the development of high-current or energetic arc discharges such as disclosed in the applications of John S. Luce, Serial No. 738,242, filed May 27, 1958, now Patent No. 2,920,234, issued January 5, 1960, and Serial No. 748,771, filed July 15, 1958, now Patent No. 2,927,232, issued March 1, 1960; the development of a method for trapping atomic ions in a magnetic field by dissociation of injected highly energetic molecular ions by an energetic arc discharge, as disclosed in the application of John S. Luce, Serial No. 728,754, filed April 15, 1958; and the development of the method of "burnout" by ionization of neutral particles in a plasma producing device as disclosed in the application of Albert Simon, Serial No. 732,770, filed April 28, 1958.

The apparatus set forth in the application of Albert Simon, aforementioned, is useful and capable of producing an energetic plasma, but the size of the plasma produced is limited due to the relative small size of the apparatus. In order to provide a device in which a larger plasma may be obtained, it is necessary to make the device much larger than that set forth by Simon. However, in a very large device, it is impractical to achieve burnout of the residual neutral particles, which is a prime necessity before a plasma can grow and thus reach a size where it produces a substantial energization of the plasma. Burnout is impractical in a larger device because sufficiently large molecular ion beam currents are not readily obtainable.

Another problem which is inherent in the Simon method is the existence of the arc within the plasma boundaries. This arc may be thought of as constituting a body which introduces impurities which tend to cool the plasma and it contains ions which are cooler than the plasma by several orders of magnitude. The injection of highly energetic ions is very effective in cleaning up these impurities, but it is quite costly to feed sufficient energetic fuel to a large device at a rate as fast as it is being burned.

With a knowledge of the above problems related to the apparatus set forth in the Simon application, aforementioned, in the production of substantial energization of the plasma, the problem of cleaning up impurities in such an apparatus and the feeding problem in a large device, it is a primary object of this invention to provide a controlled plasma and neutron producing device in which burnout can be achieved, a plasma grown, and a substantial quantity of neutrons can be produced.

It is another object of this invention to provide a controlled plasma and neutron producing device in which the heat drain and the impurities inherent in the arc ignition can be disposed of.

The primary object of the invention is provision of a method for producing an energetic plasma and for producing a substantial quantity of neutrons.

It is still another object of this invention to provide a

2

device in which some electrical power can be produced from the reactions which take place in the plasma which is produced in the device.

These and other objects and advantages will be apparent from a consideration of the following detailed specifications and the accompanying drawings wherein:

Fig. 1 shows a longitudinal cross-sectional view of one embodiment of a controlled plasma and neutron producing device.

Fig. 2 shows a cross-sectional view of another embodiment of a controlled plasma and neutron producing device, and

Fig. 3 shows a schematic diagram of a method for converting heat from the reactions in the device of Fig. 1 into electrical power.

The objects stated above have been achieved in the present invention by providing mirror coils which provide a temporary magnetically confined subvolume region, said coils at startup having, for example, about one-fifth their normal operating values, initiating a plasma within this region by, for example, injecting high-energy molecular ions in an amount in excess of the critical input current for burnout (see the Simon application, supra, Fig. 2) into the temporary region into the path of an energetic arc such as disclosed in the aforementioned Luce applications, where a portion of the injected molecular ions are dissociated into atomic ions, which are trapped by the magnetic field. The input current of the injected molecular ions is continued at this value until a sufficient number of neutrals are ionized so that a hot plasma is then formed. Immediately following the formation of the hot plasma, the magnetic fields in all regions including the temporary mirrors will be increased, say by a factor of about 5. Simultaneously, the arc is shut off, high-energy injection is discontinued and injection of "cold fuel" at an angle greater than the critical angle for containment and through the mirror region, for example, is begun. "Cold fuel" as used herein is fuel of a temperature below that for optimum reaction rates, as fully discussed below. The addition of sufficient cold fuel causes the temperature of the plasma to fall. The injection preferably continues until the temperature falls to that corresponding to the maximum reaction rate for a given machine. At that time the cold feed is adjusted to maintain the optimum reaction temperature. After the subvolume is filled with a hot plasma, the reacting volume is gradually increased by proper manipulation of current in the magnetic coils surrounding the device and the fuel feed controlled until the entire working volume of the device is filled with an energetic plasma. Finally, the plasma temperature is reduced to an operating value corresponding to the injection of fresh fuel as rapidly as fuel is lost and burned.

A brief description of the subject matter of the aforementioned applications will now be given to provide a better understanding of the operation of the instant invention.

In the application of John S. Luce, Serial No. 738,242, filed May 27, 1958, now Patent No. 2,920,234, issued January 5, 1960, there is disclosed an apparatus for producing an energetic carbon arc discharge suitable for dissociation of molecular ions into atomic ions. In that application, an energetic carbon arc is produced between widely spaced carbon electrodes disposed in an evacuated chamber and in a strong magnetic field. At startup, gas is fed to the face of a bored cathode, a R.F. voltage source is temporarily applied between the electrodes and a variable operation potential is also applied between the electrodes. After the arc is struck, the gas feed is stopped and the R.F. voltage source is disconnected and the arc is sustained by carbon ions and electrons released from the electrodes. Arc currents of 300 amperes and above are obtainable with this carbon arc.

In the applications of John S. Luce, Serial No. 748,771, filed July 15, 1958, now Patent No. 2,927,232, issued March 1, 1960, and Persa R. Bell and John S. Luce, Serial No. 750,834, filed July 24, 1958, now Patent No. 2,920,235, issued January 5, 1960, there are disclosed apparatuses for producing an energetic deuterium arc discharge which is also suitable for dissociation of molecular ions into atomic ions. In those applications, an energetic gas discharge is produced between a hollow elongated cup-shaped cathode electrode and a hollow anode electrode disposed in an evacuated chamber and in a strong magnetic field. Deuterium gas is fed to the inside of at least one of said hollow electrodes at the base thereof at a controlled rate such that nearly complete space charge neutralization occurs within the hollow cathode and causes the arc discharge to terminate from within the hollow cathode. As in the carbon arc, described above, an R.F. voltage source is used to help initiate the discharge and is then disconnected. A variable operating potential is also connected across the electrodes. The deuterium arc depends upon cross field emission within the hollow cathode. This cross-field emission in the cathode and the cup-shaped configuration of the anode causes feed gas to be completely ionized before it leaves the electrodes. It is this complete ionization of the feed gas that permits the discharge to be very energetic and to be operated under low pressure conditions. Arc currents of 100 amperes and above are obtainable with this arc discharge using deuterium as a feed gas.

In the application of John S. Luce, Serial No. 728,754, filed April 15, 1958, there is disclosed a system for igniting a plasma of high-energy ions and containing the plasma in a strong magnetic field. In the device described in that application, high-energy molecular ions such as D_2^+ are injected into a confining magnetic field perpendicular to the lines of magnetic force. At some point in the orbit of these ions in the magnetic field, a portion of them are caused to be dissociated and/or ionized by an energetic arc discharge to form atomic ions. These resultant atomic ions have one-half the momentum of the original molecular ions, when said molecular ions are diatomic, and hence have one-half the radius of curvature in the field. If the center of the orbits of these atomic ions coincides with the axis of the magnetic field, the ions will circulate in a ring. If the center of the orbits and the axis of the machine do not coincide, the atomic ion orbit center will precess about the magnetic axis. The ions will circulate until a charge exchange occurs with one of the neutral gas atoms in the system or until some other process causes the ions to be lost.

In the application of Albert Simon, Serial No. 732,770, filed April 28, 1958, there is disclosed a method for destroying neutral particles in a thermonuclear device such as disclosed in the Luce application, Serial No. 728,754, aforementioned. In order for plasma to build up and become hot, the residual neutral atoms or particles in the device have to be destroyed and new neutral particles have to be destroyed as fast as they flood into the system. There is a critical value for the input current of the injected molecular ions at which the ions "burn out" or ionize the neutral particles as fast as they are flooding into the plasma. Since burnout is an important step in the devices described herein, a detailed discussion of this principle will be given below.

In the Simon application, the apparatus at startup will have large numbers of neutral particles in it and these neutral particles will remove hot ions from the system because of the charge exchange process. The cross section for charge exchange is a steeply decreasing function of the atomic ion velocity above about 30 kev.

$$\left(\sim \frac{1}{V^8} \right)$$

However, even at 300 kev. it has a value (for deuterons

in deuterium) of about $2 \times 10^{-18} \text{ cm.}^2$, which is very much larger than the coulomb cross section involved in energy loss and particle deflection. Every charge exchange destroys a neutral, since the "hot" ion strikes a neutral and picks up an electron, thus becoming a fast neutral particle which is not contained by the magnetic field and is readily lost to the system. The ionization caused by the fast ion will remove many neutrals by this means, since the ionization cross section, about $4 \times 10^{-17} \text{ cm.}^2$, is more than 20 times as large as that for charge exchange at 300 kev. As stated above, there is a critical value for the input atomic current at which the ions burnout the neutrals as fast as they are flooding into the plasma. Once this value is exceeded, the ions get ahead of the neutrals and the plasma builds up within the volume of containment produced by the magnetic mirror coils, hence burning out additional neutrals and the system cleans out the neutrals in the plasma interior.

To determine the actual magnitude of critical current, pressure, and other controlled conditions, the effect of burnout by energetic ions has been investigated numerically. The buildup of ion density in the plasma in a mirror-type device such as disclosed in the Simon application, and also in the sub-volume formed by the temporary mirrors in the instant application, can be expressed by the time-dependent equations:

$$\frac{dn_+}{dt} = \frac{I_+}{V} - n_+^2 \sigma_0 v P - n_+ n_0 \sigma_{ex} v \quad (1)$$

and

$$\frac{dn_0}{dt} = \frac{Nv_0 S}{4V} - \frac{n_0 v_0 S}{4V} - n_0 n_+ (\sigma_i + \sigma_{ex}) v \quad (2)$$

where:

n_+ = atomic ion density

n_0 = neutral density

I_+ = atomic ion current

S = surface of area of plasma

N = density of neutrals in external manifold, which is substantially $3 \times 10^{16} \times$ pressure in mm. Hg

P = the probability of scattering into the "escape cone," and is approximately equal to $1 - \cos \theta_c$

V = volume occupied by the plasma

v = velocity of ions

v_0 = thermal velocity of neutrals

σ_0 = coulomb "cross section" in the plasma for scattering by multiple small-angle collisions through 90 degrees

σ_{ex} = charge exchange cross section

σ_i = ionization cross section

The escape cone referred to in term "P" above is that region bounded by a surface forming an angle with the axis equal to the critical angle for containment. This critical angle (θ_c) is obtained from the expression:

$$\sin \theta_c = \sqrt{\frac{1}{R}}$$

where R is equal to the mirror ratio; that is, the ratio of the maximum magnetic field strength in the mirror region (on the axis inside the mirror coils) to the maximum of that in the central region between the mirror coils. The external manifold, referred to in term "N" above is that region external to the inner chamber bounded by inner liner 7, baffles 3, and baffles 4, in the Simon application.

The charge-exchange cross-section values may be taken from the measured values published in "Physical Review" 103, 896 (1956), assuming for deuterons that the cross-section is the same as that for hydrogen at the same relative velocity. The value is $5.5 \times 10^{-18} \text{ cm.}^2$ at 250 kev., for example. The ionization cross-section values may be computed from the formula given by Bethe and Ashkin, Experimental Nuclear Physics, vol. 1, part II, published in 1953. The value is $1.0 \times 10^{-16} \text{ cm.}^2$ at 250

kev., for example. The coulomb cross-section values may be computed from the formula

$$\sigma_0 = 20\pi \left(\frac{e^2}{E_t} \right)^2$$

where e is the charge on the electron, and E_t is the average energy of an ion in the plasma.

In the first equation above, the first term on the right represents the constant source input; the second term takes into account mirror losses; and the third term represents loss by charge exchange. In the second equation above, the first term on the right represents the streaming of neutrals into the plasma; the second term represents the outstreaming from the plasma; and the third term shows the effects of neutral burnout by ionization and charge exchange.

As discussed above, burnout occurs at the critical point at which the neutrals are being ionized at a rate equal to the rate of their entry into the system. The average number of neutrals ionized by a fast ion before the ion itself is lost can be expressed as

$$\left(\frac{\sigma_i + \sigma_{ox}}{\sigma_{ox}} \right)$$

Therefore, the critical value of input current to obtain this critical point may be expressed approximately as:

$$I_c = \left(\frac{\sigma_{ox}}{\sigma_i + \sigma_{ox}} \right) I_0 \quad (3)$$

where I_0 is the total current of neutrals streaming into the plasma as defined by the formula:

$$I_0 = \frac{SNv_0}{4V}$$

The input current I_c used is the value of atomic ion current produced as a result of dissociation and/or ionization of the molecular ion beam. Since the neutral in-streaming varies linearly with pressure, the value of critical current also varies linearly with pressure.

Burnout is not a suddenly occurring phenomenon as the current is increased, but rather a smooth transition over a relatively narrow range of current. It has been shown that for currents well above the critical value, the steady-state neutral density, n_0 , can be expressed as:

$$n_0 = N_0 \left[\frac{v_0 S}{4(\sigma_i + \sigma_{ox})} \sqrt{\frac{\sigma_e P}{I + v V}} \right] \quad (4)$$

This shows that the neutral density approaches zero as I_+ becomes very large.

Referring now to Fig. 1, which illustrates one apparatus in which the principles of this invention may be carried out, a cathode 8 is mounted in member 33 and an anode 9 is mounted in a breeding blanket 1. It may be desirable to place the anode at the extreme right end of the reactor, outside the permanent mirror and thus to run the arc over the entire length of the machine. Gas from a source 34 is fed through a tube 35 to the inside of cathode 8. An arc-initiating-assisting means such as a R.F. voltage source 36, which may be a conventional welding source, is connected at one side to cathode 8 by leads 37 and 38, and is connected at its other side to anode 9 by lead 39, switch 40, lead 41, and lead 42. An arc operating potential, such as a variable direct current source 43 is connected at one side to the cathode 8 by leads 44 and 38, and is connected at its other side to anode 9 by lead 45, switch 46, lead 47, and lead 42. An energetic arc discharge 10, which passes through opening 28 in end plate 14, opening 29 in breeding blanket 1, and follows the magnetic field lines as set up by the magnetic mirror coils as shown, may be initiated and sustained by apparatus such as disclosed in either of the aforementioned Luce applications.

The reaction chamber 26 is defined by the breeding blanket 1 which is surrounded by magnetic mirror coils

2 and 3 and by a plurality of solenoid coils 17 disposed in end-to-end relation between the mirror coils 2 and 3, and a pair of end plates 14 and 15 which are mounted by electrical insulators 31 and 32, respectively, to the outside chamber wall 21. The end plates are thus insulated so that they may become charged by ions and repel further ions back into the reaction volume, and so that a current may be drained therefrom to obtain electrical power directly. The solenoid coils 17 are also used to provide the temporary mirror regions. The reaction chamber 26 is evacuated by vacuum pumps, not shown, through tubular members 24 and 25. An outer vacuum chamber 30 which encloses the reaction vacuum chamber 26, is evacuated by vacuum pumps not shown through tubular members 22 and 23. High energy molecular ions, for example D_2^+ of 600 kev. energy, are injected from a source 4, through an accelerator tube 5, through tube 48, and through an opening 16 in one of the solenoid coils 17 and the blanket 1, and then into the path of the energetic arc discharge 10, where a portion of them are dissociated to form a magnetically trapped circulating ring 7 of atomic ions in a manner set forth in the aforementioned Luce application, Serial No. 728,754. Heat from the reactions that take place in the chamber 26 and the nuclear reactions that take place in the breeding blanket 1 will be removed by circulating a pressurized liquid through tubes 18 disposed in the blanket 1, through tubes 20 disposed adjacent to the end plate 14, and through tubes 19 disposed adjacent to the end plate 15. Fig. 3 shows a schematic system for converting this heat into electrical energy.

The accelerator tube 5, referred to above, may be energized by a conventional high voltage generator. A suitable high current source of molecular ions from source 4 may be provided by apparatus such as set forth on page 18 of Nucleonics, vol. 9 (3), 1951; Rev. Scientific Instruments, vol. 24, p. 394, 1953, for example, or that described by Von Ardenne, "Tabellen der Elektronenphysik, Ionenphysik und Übermikroskopie," VEB Deutscher Verlag der Wissenschaften, Berlin, 1956 (Duo-Plasmatron).

Once burnout is achieved by the method set forth above and high energy molecular injection is stopped, cold neutral fuel is then injected as a beam 13 from a source 11, through a tube 12, which may constitute an accelerator if it is desired to impart energy to the fuel, and through entrance conduit 49 into the plasma region. In a mirror type machine, such as illustrated in Fig. 1, it is difficult to inject cold gas into the interior of a plasma at an angle less than the critical angle for containment due to the short life of a cold atom. The mean life of an atom in a plasma is:

$$t = \frac{1}{n\sigma v}$$

where n is equal to the ion density, v is equal to the ion velocity, and σ is equal to the ionization cross-section. The cross-section (σ) is about 10^{-16} cm.² for the device in consideration, and t is then equal to about 10^{-6} sec. It therefore follows that the mean distance a room-temperature atom can penetrate into the plasma before it becomes ionized is a fraction of a centimeter. Since a cold ion is incapable of crossing the magnetic field, cold atoms injected from the side are prevented from reaching the plasma interior. A solution to this problem is to inject the cold fuel particles (neutrals and/or ions) through one of the mirrors at an angle greater than the critical angle for containment. This critical angle is obtained from the formula:

$$\sin \theta_c = \sqrt{\frac{1}{R}}$$

where R is equal to the mirror ratio as discussed above and in the aforementioned Simon application. Upon ionization, the injected particle is then trapped between the mirrors and will move into the plasma along the field

line which it is on. The neutral atom trajectory may be chosen so that this field line is an interior field line of the plasma.

It has been determined that a mirror ratio of about 3.5 to 1 is required for insuring the production of a copious quantity of neutrons when a 50-50 mixture of deuterium and tritium is used as cold fuel feed, and the magnetic field must everywhere be strong enough to contain most of the alpha particles produced in the D-T reaction. A D-D reaction is not possible in magnetic mirror machines without extremely high mirror field ratios, which makes such a machine uneconomical.

The problem of tritium conservation in a D-T device requires that almost exactly one tritium atom can be produced for every neutron produced in a 50-50 D-T mixture. It will, in fact, be desirable to breed extra tritium to the maximum extent possible. This would necessitate surrounding the reaction tube with a blanket 1 consisting mostly of lithium. In addition to the lithium, the blanket 1 would consist of water, beryllium, and iron. The water is used to moderate the neutrons rapidly, while the beryllium produces extra neutrons by $(n, 2n)$ reactions. The iron is used to contain the lithium and water separately. The tritium thus produced in the blanket may then be recovered by conventional methods.

In the apparatus, illustrated in Fig. 1, the reaction tube radius is 60 cm., the blanket thickness is 60 cm., the inner diameter of the coils is 240 cm., the outer diameter of the coils is 480 cm., and the length of the reaction chamber is 50 meters. The width of the blanket 1 and of the coils 17 are not shown in their true perspective with respect to the radius of the reaction chamber 26 because of space limitation on the drawing.

In the initial stage of operation of the apparatus of Fig. 1 having the dimensions referred to above, a sub-volume of the entire device is isolated magnetically by suitably energizing different sections of the coils 17. An additional temporary mirror is produced about one meter from the mirror 2 with a mirror ratio of 3.5 to 1. The temporary mirror formed by the coils 17 is shown by the dashed, bowed-in field lines in Figure 1. The sub-volume formed by the temporary mirror and the permanent mirror is then substantially equal to the reaction chamber of the aforementioned Simon application. The entire field strength in this region is established at a value about $\frac{1}{5}$ of its normal operating value. Thus, the field in the midplane of the sub-volume is about 6 kilogauss on the axis and is 21 kilogauss in the coils. The next section of field coils immediately following the temporary mirror is reversed in current direction. This is done in order to obtain some field lines which run up into the wall region as shown by dashed lines on the drawing.

A high-energy vacuum carbon arc or high-energy deuterium arc is now struck between the cathode 8 and the anode 9 in a manner as set forth in the aforementioned Luce applications. Once the arc has been struck, injection of molecular D_2^+ or DT^+ ions at energies of about 600 kev. and a current of about one ampere or greater is begun by use of a cascade accelerator 5 as discussed above.

The initial pressure in the reaction chamber 26 is maintained at a value of about 10^{-6} mm. Hg. The injected molecular beam 6 is passed through the arc discharge 10 where a portion, for example, 25%, of the molecular ions are dissociated and are trapped by the magnetic field and form a circulating beam 7 of atomic ions.

The initial condition which must be attained is that of "burnout." The pressure is low enough and the trapped beam is large enough so that the neutral particles which are flooding into the active volume are ionized by ionization and charge exchange as fast as they enter. The neutral density drops and the plasma begins to build up thus burning out more neutrals. Hence, the system cleans out the neutrals in the plasma interior. An injected current of one ampere produces a "critical" input current of

atomic ions greater than that required for burnout in the sub-volume which is necessary for the neutrals to be destroyed. Once burnout has occurred in the sub-volume, the burnout condition will be maintained in the plasma interior. Simple calculations show that burnout will continue to exist as the sub-volume is expanded to encompass the entire plasma volume.

The achievement of burnout will be immediately followed by the formation of a hot plasma in the sub-volume. The resultant ion density is determined by the balance between trapped current and mirror losses, with the proviso that $\beta \leq \frac{1}{2}$. The term β is defined as the ratio of plasma pressure to magnetic field pressure. The unit used for these pressures is dynes per square centimeter. The ratio of these two pressures may be obtained from the equation $\beta = nkT/(B^2/8\pi)$, where n is the particle density, T is the temperature in ° K., k is Boltzmann's constant, and B is the magnetic field strength in gauss. It is hoped that for values of β less than $\frac{1}{2}$ the plasma will be held in stable equilibrium by the magnetic field. With a field of 10 kilogauss, $P=0.15$, and with an input trapped current of 200 ma., the particle density is limited by $\beta=\frac{1}{2}$ condition for energies of the order of 100 kev. or greater. Hence, the input current may be reduced immediately after burnout so as to end up with a plasma with a $\beta \leq \frac{1}{2}$.

The term P , referred to above, is the probability of scattering into the escape cone, as discussed above, and is approximately equal to: $1 - \cos \theta_c$, or

$$30 \quad P \approx 1 - \sqrt{1 - \frac{1}{R}}$$

For a mirror ratio of 3.5:1, which is the case for the apparatus illustrated in Fig. 1, then $P=0.15$.

Immediately following the formation of the hot plasma, the magnetic fields in all regions (including the temporary mirror) will be increased by a factor of about 5. Thus, the end mirror and temporary mirror rise to 105 kilogauss while the midplane field of the sub-volume goes to 30 kilogauss. Simultaneously, the arc is shut off, high-energy injection is discontinued and injection of "cold" fuel of a 50-50 mixture of deuterium and tritium is begun from source 11 and at an angle greater than the critical angle for containment as discussed above. The principle reason for increasing the magnetic fields is to reduce the Larmor radius of the charged reaction products (He^4) sufficiently to enable them to avoid the walls of the reaction chamber.

The addition of sufficient "cold" fuel causes the temperature of the plasma to fall. The injection continues until the temperature falls to a value commensurate with maximum reaction rate (calculated as being about 78 kev.) for the device described hereinafter. At that time, the "cold" feed is adjusted to maintain the temperature at this optimum value. It should be noted that any impurities in the plasma that are due to the arc ignition technique will vanish rapidly after cold-fuel injection of deuterium and tritium gas is begun.

If the average energy of the plasma is above a first steady operating point (plasma temperature corresponding to thermally stable steady-state operation) and below a second steady operating point (between 60 kev. and 122 kev. for $P=0.15$), there is an intrinsic tendency for the plasma to heat itself up. On the other hand, if "cold" fuel is injected faster than it is being lost from the system, this has a tendency to depress the temperature of the plasma. By balancing these two effects, it is possible to maintain the average energy at a fixed level and to increase the total fuel in the volume steadily. The next step will then be the gradual motion of the temporary mirror to the right (Fig. 1) by selective adjustment of current to the solenoid coils 17, by means, not shown, with a consequent filling of the entire working volume. This adjustment of current to the solenoid coils comprises increasing the current to a coil 17 to the right 75 of the temporary mirror region to a value so as to pro-

vide a new temporary mirror region having a field strength of 105 kilogauss while at the same time reducing the current to the coil 17 which formed the initial temporary mirror region to a value which provides a field strength of 30 kilogauss. This procedure is repeated step by step until the temporary mirror field is finally moved adjacent to the mirror field provided by coil 3, after which the temporary mirror field is removed by reducing the current to the coil 17 adjacent to mirror coil 3 to its normal operating value so as to provide a field strength of 30 kilogauss. The hot plasma is then confined in the entire magnetic volume provided between mirror coils 2 and 3 and solenoid coils 17. As discussed below the entire device can be filled in about 45 seconds and the temporary mirrors provided by coils 17 will need no special windings, since a temporary overload of a section of winding for an interval of this duration should be of no consequence. The final step is the reduction of the plasma temperature to the first steady operating point (calculated to be about 60 kev.).

The theory of the mode of operation for the balancing effect mentioned in the preceding paragraph is developed below:

Assume that the magnetic pressure remains constant and that the plasma pressure also is kept fixed. In this case, the rate of change of the number of particles in the plasma is:

$$\frac{d(nV)}{dt} = I - n^2 \sigma_e v PV - 2n_D n_T \sigma_{DT} v V \quad (5)$$

Here n denotes the total ion density ($n = n_D + n_T$), σ_e is the "coulomb cross section" for 90-deg. scattering by repeated small-angle collisions, and v is the relative collision velocity. The injected particle current of ions is denoted by I , and V is the total volume of the plasma.

Similarly, the time rate of change of the energy of the system, $\bar{E}$ is given by the equation:

$$\frac{d(n\bar{E}V)}{dt} = V n_D n_T \sigma_{DT} v [E_a(1 - P) - 2\bar{E}] - V n^2 \sigma_e v P \bar{E} - P_{brems} V - \frac{4}{3} n \bar{E} \frac{dV}{dt} \quad (6)$$

where E_a (=3.5 mev.) is the energy deposited in the gas by the He^4 reaction product, and P_{brems} is the bremsstrahlung loss. The last term on the right represents the work done against the magnetic field by the plasma. The pressure, on the assumption that the electron and ion temperatures are equal, is $4/3n\bar{E}$. At constant pressure,

$$n\bar{E} = \text{constant} \quad (7)$$

Hence

$$\frac{7}{3} n \bar{E} \frac{dV}{dt} = V [n_D n_T \sigma_{DT} v E_a(1 - P) - P_{brems}] - [2n_D n_T \sigma_{DT} v + n^2 \sigma_e v P] E V = \bar{E} V (f - 1) (2n_D n_T \sigma_{DT} v + n^2 \sigma_e v P) \quad (8)$$

where

$$f = \frac{n_D n_T \sigma_{DT} v E_a(1 - P) - P_{brems}}{E [2n_D n_T \sigma_{DT} v + n^2 \sigma_e v P]}$$

is the ratio of the power deposited in the fuel minus the bremsstrahlung loss to the energy required to heat the fresh fuel injected at the steady state value to the operating temperature. Thus, for fixed pressure, the volume will increase with time if $f > 1$ and decrease if $f < 1$.

Of course, this result is dependent on the conditions being consistent with Equation 5. In particular, if we wish to keep both n and $\bar{E}$ fixed, this requires that

$$\frac{7}{3} n \bar{E} \frac{dV}{dt} = \frac{7}{3} \bar{E} (I - n^2 \sigma_e v PV - 2n_D n_T \sigma_{DT} v V) \quad (9)$$

as follows from Equation 5 by multiplication by $7/3\bar{E}$.

On comparison with Equation 8, this shows that

$$\frac{I}{V} = \left[\frac{3}{7} (f - 1) + 1 \right] (n^2 \sigma_e v P + 2n_D n_T \sigma_{DT} v) \quad (10)$$

Hence, neutral gas must be fed in at a rate specified by Equation 10, which is greater than the loss rate if $f > 1$ and smaller if $f < 1$.

If we wish to increase the plasma volume at the maximum possible rate, we must operate at the peak of the f function. This peak occurs at about $E = 78$ kev. for $P = 0.15$ and has the value $f = 1.3$. Hence by Equation 8

$$\frac{1}{V} \frac{dV}{dt} = \frac{3 \times 0.3}{7n} (2n_D n_T \sigma_{DT} + n^2 \sigma_e v P) \quad (11)$$

The volume will increase exponentially with a time constant T which is

$$\frac{7}{3(f-1)} T = \frac{7n}{3 \times 0.3 \times [2n_D n_T \sigma_{DT} v + n^2 \sigma_e v P]} \quad (12)$$

Naturally, by Eq. 10, the neutral feed will necessarily increase exponentially as well.

For our conditions,

$$T \approx 0.84 \text{ sec.}$$

and

$$T = 6.5 \text{ sec.}$$

The total expansion of volume required to fill the entire device is of the order of 10^3 . Hence, the time required is about

$$T_{\text{tot}} = 6.9T = 45 \text{ sec.}$$

Thus the entire device can be filled in about 45 sec.

This result also shows that the temporary mirrors will need no special windings, since a temporary overload of a section of winding for an interval of this duration should be of no consequence.

In order that the plasma maintain its own temperature, it is necessary that the energy deposited in the gas by the charged particles equal the energy lost by bremsstrahlung plus the energy needed to heat incoming cold gas particles to the temperature of the system. The energy deposited per unit volume per unit time is

$$P_{\text{dep}} = n_D n_T \sigma_{DT} v E_a (1 - P) \quad (13)$$

where

n_D = deuterium ion density

n_T = tritium ion density

σ_{DT} = nuclear cross section

v = relative velocity

E_a = energy of charged alpha particle (=3.5 mev.)

$1 - P$ = probability that the alpha particle is not emitted into the mirror loss cone

If the plasma particles are distributed according to a Maxwell-Boltzmann law, the quantities σ and v should be replaced by $\bar{v}v$. This denotes the average of σv over a Boltzmann distribution. In a mirror machine, however, there will be a peaking of the distribution toward the higher end, owing to the preferential loss of colder ions through the mirrors. For this reason, σ and v will be calculated by assuming an isotropic one-velocity distribution of ions with an energy equal to the average energy of the plasma particles. In this case

$$\bar{v}^2 = \frac{1}{2} \int_{-1}^{+1} (v_D^2 + v_T^2 - 2v_D v_T \cos \theta) d \cos \theta \\ = v_D^2 + v_T^2$$

Hence we choose

$$\bar{v} \cong \sqrt{v_D^2 + v_T^2} = \sqrt{\frac{2\bar{E}}{M_D} + \frac{2\bar{E}}{M_T}} \\ = \sqrt{\frac{10\bar{E}}{3M_D}} \quad (14)$$

where

$\bar{E}$ = average energy of an ion in the plasma

M_D = deutron mass

M_T = triton mass

11

By similar reasoning, the effective bombarding energy of the deuteron is

$$E_D \approx \bar{E} + \frac{2}{3}\bar{E} = \frac{5}{3}\bar{E}$$

The power lost per unit volume due to bremsstrahlung is

$$P_B = \frac{64\pi^2 z^2 n^2}{3\sqrt{2\pi m \hbar c^3}} \sqrt{\frac{2\bar{E}}{3m}} \quad (15)$$

where

n =total ion density= $n_D + n_T$

m =electron mass

The power required to heat the incoming fuel is

$$P_{\text{fuel}} = I_{\text{in}} \bar{E} \quad (16)$$

Since at equilibrium the sum of the particle loss through the mirror and the loss by burning in the reaction must be equal to the input current, the input current per unit volume is:

$$I_{\text{in}} = n^2 \sigma_e v P + 2n_D n_T \sigma_{DT} v \quad (17)$$

The first term on the right accounts for mirror loss of fuel. Thus, σ_e is the coulomb cross section for scattering through 90 deg., and the mirror escape probability per 90 deg. collision is denoted by P . The second term accounts for fuel lost by nuclear reactions.

Note that a mirror ratio of 3:1 is too small to permit operation at constant density. For a mirror ratio of 3.5, however, operation at constant density is possible at either $\bar{E}=60$ kev. or $\bar{E}=122$ kev. Now the lower the operating temperature of a system, the higher the density for fixed magnetic field strength ($nkT \approx B^2/8\pi$) and hence the higher the specific power in the plasma. This is normally desirable, since it results in smaller over-all devices and lower capital costs. For this reason, we choose the operation of our device to be at $\bar{E}=60$ kev. with a mirror ratio of 3.5:1. Note also that the point $f=0$ is the true ignition temperature. The gas, at that temperature or above, will continue to burn (though at a decreasing rate) in the absence of cold feed.

Once the operating temperature of the system has been decided, the maximum density may be determined by specifying a value of the magnetic field. Assume that $B=30,000$ gauss. Then

$$n_e k T_e + n_i k T_i = \beta \frac{B^2}{8\pi} \quad (18)$$

where β is the maximum ratio of material pressure to magnetic pressure. Assume that a maximum value of $\beta=1/2$ can be achieved. Now if the electrons and ions are at the same temperature and have equal densities,

$$n_i = \frac{1}{2} \frac{B^2}{8\pi} \cdot \frac{1}{2kT} = \frac{B^2}{32\pi \cdot 2/3\bar{E}} \quad (19)$$

$$= 1.35 \times 10^{14} \text{ cm.}^{-3}$$

The mean residence time in the mirror system is

$$\tau \approx \frac{1}{n_i \sigma_e v} \quad (20)$$

For $P=0.15$, this yields

$$\tau = 0.45 \text{ sec.} \quad (21)$$

Finally, the specific neutron production rate is

$$N = n_D n_T \sigma_{DT} v = 1.5 \times 10^{13} \text{ cm.}^{-3} \text{ sec.}^{-1}$$

As the radius of the device is increased, the nuclear power yield per unit length increases as the square of the radius. On the other hand, the total magnet power required does not change as long as the ratio of outer coil radius to inner coil radius is kept fixed.

We consider the device to be a long solenoid. This approximation should be valid, except near the mirrors. In that region, the actual magnet power will be somewhat larger than that calculated by this method.

The magnetic field in a solenoid is given by the relation

12

$$B = \frac{4\pi J}{10} \quad (23)$$

where J is the number of ampere turns per unit length.

5 If the inside and outside radii of the coils are denoted by r_1 and r_2 , respectively, and s is defined as a space factor equal to the fraction of the gross cross section of the coil which is occupied by solid conductor, then

$$10 \quad I = \frac{J}{(r_2 - r_1)s} \quad (24)$$

where I is the current density in the conductor. Hence

$$15 \quad I = \frac{10B}{4\pi s(r_2 - r_1)} \quad (25)$$

The ohmic power in the coils per unit length of the solenoid is then

$$P_m = I^2 p V \quad (26)$$

20 where p is the resistivity of the conductor and V is the volume of the conductor per unit length of the solenoid. Now

$$V = \pi s(r_2^2 - r_1^2) \quad (27)$$

Hence, by Equations 25, 26 and 27, the magnet power 25 per unit length of the solenoid may be written as

$$P_m = \frac{25(r_2 + r_1)B^2 p}{4\pi(r_2 - r_1)s} \quad (28)$$

The resistivity of copper at 20° C. is about 2×10^{-8} 30 ohm-cm. In addition, as will be seen, the power density in the coils will be quite low. Hence, the space factor 35 in r_2/r_1 is somewhat arbitrary. Large values of this ratio yield low values of the total magnet power, but at the expense of large capital investments in copper. We assume that $r_2/r_1=2$ will be a reasonable choice.

For a field of 30 kilogauss, we obtain

$$40 \quad P_m = \frac{25}{4\pi} \frac{3}{1} \frac{2 \times 10^{-8}}{0.8} \cdot (3 \times 10^4)^2$$

$$= 1.34 \times 10^4 \text{ w./cm.}$$

$$= 1.34 \text{ mw./m.}$$

In steady state, "cold" fuel will be injected as fast as 45 it is being lost. This rate has been determined to be 3×10^{21} atoms per second, or approximately 0.10 liter per second of mixed deuterium and tritium gas at normal temperature and pressure (some of this "cold" feed 50 may be in the form of material being returned to the system by the end plates).

The steady-state characteristics of the device of Fig. 1, as described above, is summarized in the following table:

Steady-state characteristics

55	Average plasma energy	.. 60 kev.
55	Mirror ratio	.. 3.5 to 1.
55	Fuel composition	.. 50% D, 50% T.
55	Ion density	.. 1.35×10^{14} ions/cm. ³
55	Magnet field (solenoid)	.. 30 kilogauss.
60	β	.. $\frac{1}{2}$.
60	Mean residence time	.. 0.45 sec.
60	Specific neutron production	.. 1.5×10^{13} neutrons/cm. ³ /sec.
65	Plasma radius	.. ≈ 38 cm.
65	Reaction tube radius	.. 60 cm.
65	Flux on reaction tube	.. wall .. 6.05×10^{13} neutrons/cm. ² /sec.
65	Magnet power	.. 1.34 mw./m.
65	Blanket composition	.. Li, H ₂ O, Be, Fe.
65	Blanket thickness	.. 60 cm.
70	Coil I.D.	.. 240 cm.
70	Coil O.D.	.. 480 cm.
70	Length	.. 50 m.
70	Total heat power	.. 402 mw.
75	Total magnet power	.. 67 mw.
75	Total weight of copper	.. 5.4×10^3 tons.

The energetic plasma produced in the device of Fig. 1 will effect the production of a quantity of neutrons and a large amount of energy. In addition, energy is produced by the (n, γ) reaction in the lithium blanket. As has already been mentioned, this energy will be taken off in the form of heat from the blanket, tube wall, and end plates and will be put through a conventional heat cycle. Fig. 3 shows such a conventional heat cycle in which electrical power is produced.

For example, pressurized water flows through the coils in the blanket and those adjacent the end plates, and enters a conventional heat exchanger where it gives up its heat to generate steam. The steam drives a turbo-generator to produce electric power in the conventional manner.

The principles set forth above may be employed in a device which is toroidal in shape. This presupposes that current theoretical ideas for making a successful toroidal container are correct. Such a device is illustrated in Fig. 2. The device of Fig. 2 may involve the use of the energetic arc for substantially the full length of the reactor although operation of a shorter arc in the manner of Fig. 1 is also feasible. The arc is terminated after burnout followed by a magnetic field increase, and relatively low energy fuel injection is used to feed the plasma after burnout, in the same manner as set forth in the operation of Fig. 1 above. The arc electrodes are positioned in a region of widely diverging magnetic fields (a temporary condition) so that the field lines intersect the walls of the reaction tube. A temporary mirror region is established, as shown in Fig. 2, near the diverging region to form a static mirror region. This static mirror region is shown by the dashed bowed-in field lines adjacent to where tube 65 enters into the reaction chamber. In addition, a moveable mirror region is established to the right of the static mirror region as shown by the dashed bowed-in field lines. A small reacting plasma is initiated, by means described above for Fig. 1, in the sub-volume between the static mirror and the moveable mirror. When "burnout" conditions have been achieved and the sub-volume filled, the magnetic field is increased to the value necessary for the containment of reaction products, the arc is extinguished, cool fuel injection is substituted, and the moveable mirror is progressively moved away from the static mirror until it eventually is beside the opposite side of the diverging region. At this point, the field in the diverging region is returned to normal, and both of the mirror fields are removed. Alternately, the field in the diverging region may be returned to normal when the arc is extinguished.

In Fig. 2, a cathode electrode 55 is insulatingly mounted in a space in one of the solenoid coils 71, and anode electrode 56 is insulatingly mounted in one of the solenoid coils 71. These electrodes are so positioned that the arc discharge 57 which is initiated between them passes through holes 75 and 76 in the blanket 70 and reaction tube 74 and then follows the magnetic field lines as shown by the dashed lines in the figure. The reaction chamber 72 is formed by the tubular member 74 shaped in the form of a toroid as shown. This tube is surrounded by a breeding blanket 70. This blanket 70 is in turn surrounded by the solenoid coils 71. Additional coils, not shown, are provided to establish a system of transverse magnetic fields perpendicular to the axial confining field, to insure stability of the plasma. The direction of these transverse fields rotates with axial distance around the torus. A helical confining field is a simple form of such transverse field, for example. Heat from the reaction tube and the reactions that take place in the blanket 70 is removed by pressurized fluid which is circulated through tubes 69 mounted in the blanket 70. This heat is then converted into electrical energy in the same manner as set forth for Fig. 1 above. The reaction tube is evacuated by vacuum pumps not shown, through tubular members 67 and 68. Proper energization of the solenoid coils 71

provides the diverging magnetic fields and the temporary mirror fields as shown on the drawing. High energy molecular ions are injected into subvolume 73 from a source 58, through accelerator tube 59, and through tube 60 in the form of a beam 61 which beam passes through arc discharge 57 where a portion of them are dissociated to form a magnetically trapped circulating beam of atomic ions 62. When burnout has been achieved, injection of high energy molecular ions may be stopped and injection of cold fuel then started. This cold fuel during the time that a temporary mirror region exists, may be injected as a beam 66 and at an angle greater than the critical angle for containment from a source 63 through tube 64, and then through tube 65, as shown. The toroid is then 15 filled with a plasma in a manner indicated above.

The dimensions for the device of Fig. 2 are substantially the same as those for Fig. 1 above and the device of Fig. 2 operates in substantially the same manner as that set forth for Fig. 1 above and therefore a detailed description of the operation of Fig. 2 will not be given.

If a hollow deuterium arc discharge, such as disclosed in the application of John S. Luce, Serial No. 748,771, now Patent No. 2,927,232, issued March 1, 1960, aforementioned, is used in the devices of Fig. 1 and Fig. 2, then 25 the magnetic mirror fields will cause the discharge to spread out in the region between the mirrors and the plasma will then be contained within the hollow arc discharge. This condition will prevent the instreaming of cold neutrals from the vessel walls into the plasma.

30 This invention has been described by way of illustration rather than limitation and it should be apparent that the invention is equally applicable in fields other than those specified.

What is claimed is:

35 1. The method of initiating and sustaining an energetic plasma for the production of neutrons in an evacuated reaction chamber surrounded by a plurality of electromagnetic coils in end-to-end relation comprising the steps of selectively energizing some of said coils to establish a 40 relatively large first value of containing magnetic field in a small portion of said chamber to form a magnetically contained sub-volume, said sub-volume being formed by two magnetic mirror regions spaced apart axially with a uniform magnetic field therebetween and having a mirror ratio of at least 3.5 to 1; initiating an energetic arc discharge between two electrodes, said discharge passing through said sub-volume along the containing magnetic field lines; injecting a selected current of relatively high-energy molecular ions into the path of said discharge 45 where a portion of said molecular ions are dissociated and/or ionized to form atomic ions which are trapped by said containing magnetic field to form an energetic plasma in which neutrons are produced within said sub-volume, said selected current being at least greater than that required for producing a current of atomic ions sufficient to 50 achieve burnout of neutral particles in said sub-volume; increasing the magnetic field strength of said sub-volume to a value at least five times larger than said first value after said plasma is formed; simultaneously terminating said arc discharge and the injection of said high energy molecular beam, and then injecting relatively low-energy particles at a selective feed rate into said plasma until said sub-volume is filled with a plasma; then continuing said injection of said low-energy particles while at the same 55 time periodically, step-by-step increasing the length of said magnetically contained sub-volume, each said step comprising decreasing the current flow through the coil forming one of said magnetic mirror regions to return said one region to said uniform field strength, and simultaneously increasing the current flow through the next adjacent coil to thereby establish a mirror region in alignment with said next adjacent coil, until said sub-volume has 60 been expanded to encompass the entire reaction chamber and is filled with an energetic plasma and a substantial 65 quantity of neutrons.

2. The method set forth in claim 1, wherein the reaction chamber is cylindrical.
3. The method set forth in claim 1, wherein the reaction chamber is a toroid.
4. The method set forth in claim 1, wherein said reaction chamber is surrounded by a tritium breeding blanket, and wherein the said method includes the further steps of circulating a pressurized fluid through tubes disposed in said blanket to thereby remove heat caused by reactions in said chamber and nuclear reactions within said blanket, and converting said removed heat into electrical energy.
5. The method set forth in claim 1, wherein said low-energy particles include both ions and neutral particles injected at an angle greater than the critical angle for containment.
